HAT AND COAT HANGER FOR
AUTOMOBILES

Martin Meyer, Franklin County, Iowa

Application June 13, 1935, Serial No. 26,430

3 Claims. (Cl. 211—32)

This invention relates to improvements in hat and coat hangers of the type adapted to be placed in an automobile.

The object of my invention is to provide a simple, durable and inexpensive hat hanger which may be easily and quickly attached to the interior frame member of an automobile body, and when so attached provide means whereby a hat or other suitable article may be easily and quickly placed in position, and when so placed it will be firmly supported without injury to the article being supported.

More specifically, it is the object of my invention to provide a combination hat and coat hanger provided with a yieldable clamping device for clamping the hat brim, and in connection therewith means whereby the tension of the clamping means may be easily and quickly adjusted to provide means whereby the hat and brim may be easily placed in clamping position at the time the clamping mechanism is under no tension, and whereby the tension may be easily and quickly tightened to firmly hold the hat in position.

A further object is to provide in connection with a hat holder of the type above described, improved means whereby a coat supporting hook or means for carrying an assist cord may be easily connected to the hat holder.

A further object of my invention is to provide in a hat holder employing a yieldable clamping member, improved means for varying the tension of the clamping member.

My invention consists in the construction, arrangement and combination of the various parts of the device, whereby the objects contemplated are attained, as hereinafter more fully set forth, pointed out in my claims, and illustrated in the accompanying drawing, in which:

Figure 1 is an end elevation of my improved hat holder showing the manner in which the coat hanger is connected therewith, and in dotted lines the manner in which an assist cord may be connected thereto.

Figure 2 is a front elevation of my improved hat hanger with the coat hanger attachment applied thereto.

Figure 3 is a front elevation of the coat hanger removed from the hat hanger.

Figure 4 is a front elevation of a detachable element for supporting an assist cord.

Figure 5 is an end elevation of the same.

Figure 6 is a detail view showing the spring supporting yoke.

Figure 7 illustrates a filler block designed to be

placed in the notch for receiving the hat hanger attachment when said hat hanger is not used.

Figure 8 shows the upper end of modified form of assist cord.

In the drawing I have used the reference numeral 10 to indicate a portion of an automobile frame forming a portion of the body to which my improved device is attached. The hat hanger comprises a body member 11 formed preferably of pressed sheet metal, having an overhanging bracket portion 12 at its upper end, said bracket having upwardly extending flanges 13 which serve to strengthen the bracket. The body 11 is secured to the frame member 10 by means of a screw 14. The bottom end of the body 11 is provided with a downwardly extending flange 15, said flange 15 having a crescent shaped opening 16 to form an annular ring portion 17, the edges of the ring portion 17 being rounded so as to permit an assist cord to be secured to the said member 17, as illustrated in dotted lines in Figure 1. The flange 15 is spaced from the frame member 10 a slight distance to form a recess 18 between said flange and the adjacent face of the member 10.

The body portion 11 is provided with a rubber pad 19 having its front face serrated to form a gripping surface for a hat or similar article.

Pivotedly mounted on the free end of the bracket 12 I have provided a clamping arm 20, the upper end of the arm 20 being provided with a U shaped portion 21 to form a recess 22 for receiving the extreme end 23 of the bracket 12 and thus provide means for hinging the arm 20 to said bracket, the arm 20 having an arcuate portion 24, the lower end of which terminates in a forwardly curved portion 25, the lower end of which is redoubled on itself and formed with a bulged portion 26 designed to rest against the pad 19. The upper end of the portion 26 is bent rearwardly to form a horizontal portion 27 designed to enter a notch 28 formed in the body member 11.

The member 27 is mounted in the notch 28 in such a manner as to provide a guide for the member 20 to prevent lateral movement of the same as the clamp 26 is moved toward and from the pad 29. The member 27 also serves to limit the forward movement of the members 25 and 26 together by engaging the lower end of the notch 28.

Pivotedly mounted to the back edge of each side of the member 11 is a spring 30, the said springs being wound about the legs 31 of a yoke 32, said yoke being designed to slide on the arcuate por-

tion 24 from the solid line position to the dotted line position shown in Figure 1, the springs 30 serving to apply tension to the members 20 and 26 to yieldably maintain the member 26 in engagement with the pad 19. It will readily be seen that when the springs 30 are in the dotted line position a comparatively small amount of tension will be placed between the members 19 and 26, and that when the springs 30 are in their solid line position a comparatively large amount of tension will be applied to the member 26 for gripping a hat brim between the said members 19 and 26. The member 27 also serves to limit the upward movement of the brim when placed in the clamps.

In the actual operation of the hat holder the operator first moves the springs 30 to their dotted line position and then slips the hat brim between the members 19 and 26, when in its dotted line position, to support the weight of the hat. The operator then moves the yoke 32 downwardly, firmly gripping the hat brim in position. This entire operation may be accomplished with the hand supporting the hat, thus eliminating the necessity of having to use both hands to place the hat in position. The hat brim is easily inserted between the members 19 and 26 when the member 26 is under minimum tension. When under maximum tension the hat is firmly held against being blown away by excessive currents of air passing through the automobile while in motion.

Sometimes it is desired to furnish a combination hat holder and an assist cord, in which case an assist cord is formed on the annular member 17. Other times it is desirable to sell the hat holder and assist cord separately so as to permit the purchaser to obtain either the assist cord or the hat holder, or both, in which case I have provided a disc 33 having an opening 34 slightly above its center, and a downwardly extending flange 35 formed on its lower end, said flange having an opening 36 to provide an annular support 37, to which the assist cord or strap 38 may be secured in the usual manner. The disc 33 is simply placed in the recess 18 between the member 15 and the frame 10. A screw 39 is then placed through an opening 40 formed in the flange 15, and through the opening 34 into the frame 10, thus pivotally supporting the disc 33 and the assist cord so as to permit the assist cord to swing laterally, as well as forwardly and rearwardly. The screw 39 serves to assist in supporting the body 11 as well as the disc 33. Any strains applied to the assist cord are applied directly to the screw 39, which is partly supported in position by means of the screw 14, thus providing means for firmly supporting the assist cord.

In Figure 8 I have illustrated a modified form 60 of assist cord, the upper end of which is provided with a flattened portion 44 having an opening 45 for receiving the screw 39. The form illustrated in Figure 8 eliminates the necessity of the plate 33.

A filler block 46 is provided to be placed in the notch 18 when it is desired to use the device as a hat hanger only, said filler block having an opening 47 for receiving the screw 39, the filler block being for ornamental purposes only.

Sometimes it is desirable to use a coat hanger 70 in connection with the hat hanger, instead of the assist cord, in which case I have provided a disc 41, having an opening 42 above its center and a

hook 43 formed on its lower end for supporting a coat or similar article, the disc 41 being mounted on the screw 39 in place of the disc 33, in the manner clearly illustrated in Figures 1 and 2.

Thus, it will be seen I have provided a hat 5 hanger which may be cheaply constructed and in which a hat may be easily and quickly placed in position by the use of one hand, and after being placed in position may be firmly clamped therein, and at the same time provide in connection 10 therewith means whereby an assist cord or coat hanger may be used in connection with the hat hanger at the will of the purchaser, thus providing a series of articles that may be combined together in various ways to suit the requirement 15 of various purchasers. I find that oftentimes the purchaser may desire two or more hat hangers in a single automobile, and at the same time only one assist cord is desired, sometimes combining a hat hanger and assist cord, and oftentimes an- 20 other hat hanger and a coat hanger together.

I claim as my invention:

1. In a device of the class described, an upright body portion having a forwardly extending bracket at its upper end; a clamping pad carried 25 by said body; an arcuate clamping arm having one end pivotally connected to the free end of said forwardly extending bracket, the lower end of said arm having a clamping portion adjacent to the said pad; a yoke slidably mounted on the arcuate 30 portion of said clamping arm; and yieldable means supporting said yoke mounted to swing about the center of said arcuate portion whereby the tension between said pad and said clamping member may be varied by sliding said yoke over 35 the arcuate portion of said clamping arm, toward and from its pivoted end.

2. In a device of the class described, an upright body portion having a forwardly extending bracket at its upper end and an opening in its 40 central portion; a clamping pad carried by said body; an arcuate clamping arm having one end pivotally connected to the free end of said forwardly extending bracket, the lower end of said 45 arm having a clamping portion supported adjacent to said pad and an inwardly extending portion terminating in said opening to limit the swinging movement of said arm; a yoke slidably mounted on the arcuate portion of said clamping arm; and yieldable means supporting said yoke 50 mounted to swing about the center of said arcuate portion whereby the tension between said pad and said clamping member may be varied by sliding said yoke over the arcuate portion of said clamping arm, toward and from its pivoted end. 55

3. In a device of the class described, an upright body portion having a forwardly extending bracket at its upper end, the forward end of said bracket being notched; a clamping pad carried by said body; an arcuate clamping arm having its 60 upper end provided with a U shaped portion supported in said notch to form a pivot for said arm, the lower end of said arm having a clamping portion supported adjacent to said pad; a yoke slidably mounted on the arcuate portion of said 65 clamping arm; and yieldable means supporting said yoke mounted to swing about the center of said arcuate portion whereby the tension between said pad and said clamping member may be varied by sliding said yoke over the arcuate portion of said clamping arm, toward and from its pivoted end. 70

MARTIN MEYER.
